UNITED STATES PATENT OFFICE.

ARTHUR C. McWILLIAMS, OF CHICAGO, ILLINOIS, ASSIGNEE TO WESTINGHOUSE ELECTRIC & MANUFACTURING COMPANY, A CORPORATION OF PENNSYLVANIA.

METERING PANEL BOARD.

Application filed October 28, 1922. Serial No. 597,520.

My invention relates to metering panel boards of the general class employed in office buildings or apartment hotel buildings for affording the convenient connecting of consumption circuits in any desired groupings to meters. Panel boards have heretofore been employed for this purpose in a variety of forms, including types employing conductors extending transversely of each other and having the relatively transverse conductors adapted to be connected interchangeably with each other by means of plug connectors or the like, in which case the multiplicity of conducting elements thus employed has involved an undesirably high cost. They have also been employed in forms which required the various detachable connections to be made at least in part from the back of the board, thus increasing the difficulty and the time required for making any changes in such connections; also in forms requiring the detachable connections to cross other conductors, thus affording the risk of short-circuits if the changes were made while the conductors are alive and also presenting a resulting net work of wires which made it difficult to determine which of the consumption circuits were connected to each meter. Furthermore, the panel boards as heretofore employed for this general purpose require an undesirably great width, as the space for such boards is usually restricted to parts of the building in which the available width is quite limited.

My present invention aims to overcome all of the above named objections to the types heretofore in common use and aims to do so by providing an arrangement or arrangements which will be exceedingly simple to manufacture, in which all of the changeable connections can readily be made from the face of the board, in which the interchangeable connections to the meters can readily be made by means of straps of standard size and without having any conductors cross one another, and in which a glance at the panel board will readily tell which of the consumption circuits are connected to each meter. Furthermore, my invention aims to provide an arrangement for this purpose which will readily lend itself to the lateral compactness demanded by the space usually available for such panel boards, and one which will be both simple in construction

and manipulation and low in cost of manufacture and installation. It also aims to provide a construction which will readily lend itself to a variety of embodiments. Still further and also more detailed objects will appear from the following specification and from the accompanying drawings, in which

Fig. 1 is a partly diagrammatic elevation showing a three-wire panel board embodying my invention as designed for interchangeably connecting twelve consumption circuits to six or less meters, and showing a typical set of connections as employed in distributing these twelve consumption circuits over four meters.

Fig. 2 is a smaller view showing another grouping of the same consumption circuits, namely one in which a certain meter is connected to consumption circuits controlled by fusible devices at opposite sides of the panel board.

Fig. 3 is an enlarged transverse section taken along the line 3—3 of Fig. 1.

Fig. 4 is a rather diagrammatic view of another 8 circuit panel board embodying my invention but having meter terminals consisting mainly of bars extending diagonally of the rows of fusible devices.

Fig. 5 is another diagrammatic view, corresponding to one half of the main portion of the panel board of Fig. 1, but having another grouping of the fusible devices and meter bars.

Fig. 6 is another diagrammatic view of one half of a panel board, showing an embodiment employing simple posts instead of bars as meter terminals.

Fig. 7 is a transverse section taken along the line VII—VII of Fig. 1.

In my copending application No. 467,801 on a metering panel board, as filed May 9, 1921, I have shown a panel board in which the meter terminals are disposed in two parallel rows flanked on either side by the consumption circuit devices, the latter being disposed in pairs with the two fusible devices for each circuit disposed laterally of each other, the arrangement being such that connecting straps of a standard size can be used interchangeably for affording the various circuit groupings so as to connect any desired consumption circuits to any particular meter. While the panel board as thus disclosed has

demonstrated its commercial value, it still has the shortcomings of requiring the connections between the fusible devices and the consumption circuits controlled by them 5 either to be fed through the panel board from the back of the latter or to be made by unsightly wiring on the face of the board. It also has the disadvantage of requiring a greater width in proportion to the capacity 10 of the board than may be desirable in view of the space commonly allotted by the architects for such purposes.

My present invention overcomes the objections just cited by disposing the fusible devices associated with each consumption circuit vertically above one another, or in a row parallel to the rows of meter terminals, and by exposing the consumption circuit terminals of these fusible devices near the edges 20 of the panel board so that the wire connections can readily be made on the facing of the board without feeding the wires through any holes in the latter and without involving the expense required for boring such holes. 25 Furthermore, my present invention provides for a disposition of the meter terminals which can be employed equally well in embodiments having metering bars adapted to be connected interchangeably to each other 30 or to certain of the consumption circuit devices by straps of a length uniform with that required for connecting adjacent terminals of the fusible devices with each other; or in embodiments in which strips of different 35 lengths are employed respectively for the connections between adjacent terminals of the fusible devices, the connections between the meter terminals and fusible devices, and the connections between meter terminals.

40 Illustrative of my invention,

Fig. 1 shows an embodiment in which a base board 1, desirably of slate, forms the support or insulating base of the panel board. Extending longitudinally of this 45 board and medially thereof are a series of meter bars, which bars are here shown as disposed in two parallel rows alined respectively with a positive bus bar 32 and a negative bus bar 33. Each of the meter bars (which are here designated respectively as A, B, C, D, E, and F) has at each end a suitable connecting portion, such as a clamping nut 34 threaded on a pin 35 which projects 50 forwardly from the meter bar, and these connecting portions on each meter bar are desirably spaced from each other by three times the uniform center-to-center distance between the fusible devices which are respectively associated with the various consumption 55 circuits. To simplify the tracing of these consumption circuits, the two fusible devices associated with each such circuit are desirably consecutive, so that each meter bar is laterally opposite a group of four fusible devices comprising the two pairs of such de-

vices respectively controlling two consumption circuits.

Where connecting straps are to be used interchangeably for three different purposes, the first and fourth fusible device of each 70 such group has its polarity terminal 16 exposed on the face of the board and extending toward one of the said connecting portions on the meter terminal opposite that group, while the second and third fusible device of 75 each group of four has its corresponding terminal permanently connected to a neutral bus bar 17 extending along the back of the board behind the entire row of fusible devices. All of the fusible devices in the same row 80 have their consumption circuit terminals 28 exposed on the face of the board and desirably close to one edge of the latter, so that the connections to the corresponding circuit wires can readily be made by simply bringing the wires out over that edge of the board after the manner shown in dotted lines at 19, these consumption circuit wires having been omitted from the drawing as a whole to avoid confusion. Each of the polarity terminals 16 of the said first and fourth fusible devices of each group includes a clamping nut 17' threaded on a forwardly projecting stem 18, and the stems 18 are desirably 85 spaced from the nut-carrying stems 15 on the meter bars by the same center-to-center distance as that between the centers of consecutive fusible devices in the same row. Likewise, the two rows of meter bars also desirably have the same center-to-center spacing. 90

Owing to this uniformity of the spacing between the various interchangeably connectable parts, a single standard size of strap connector will serve equally well for any one of the four common purposes, namely 105 as a strap 20 for connecting a meter bar with a polarity terminal laterally adjacent thereto, as a strap 21 for connecting the fourth polarity terminal of any group with the first polarity terminal of the next group, as a strap 22 for connecting two consecutive meter bars in the same row, or as a strap 23 for connecting two laterally adjacent meter bars. Consequently, my simple arrangement readily permits such connector straps to be used 110 interchangeably for connecting the consumption circuits in any desired groupings to the meters. Thus, Fig. 1 shows circuits 1, 2 and 3 connected to the meter AA, circuits 4, 5 and 6 to the meter CC; circuits 7, 8, 9, 10, and 11 to the meter EE; and circuit 12 alone to the meter FF. In this case, the circuits at each side of the panel board are all connected to the meter panels in the row at the same side of the board, and only one totalizer 115 strap 22 is used between consecutive meter bars in the same row.

Likewise, in Fig. 2, the meter bars A or D are both connected to the circuits 1, 2, 7 and 8; meter bar B is connected to circuits 120

3, 4 and 5; meter bar C to circuit 6 only; and meter bars E and F are both connected to circuits 9, 10, 11 and 12.

However, while I have heretofore described embodiments employing highly desirable features of construction and arrangement, I do not wish to be limited to the same, since various modifications might obviously be made without departing either from the spirit of my invention or from the appended claims. For example, Fig. 4 shows an embodiment in which every alternate fusible device in each row presents a polarity terminal inwardly of the panel, in which these polarity terminals in the two rows are relatively staggered, and in which the meter terminals consist partly of bars 41 disposed obliquely of the said rows and partly of simple posts 42. In this case it will be evident from the dotted lines indicating some suggested groupings that connector straps of a single standard length can be employed for a large variety of groupings of the consumption circuits.

Moreover, my invention may also be employed without having all of the connector straps of the same length, as for example after the manner of Figs. 5 and 6. In Fig. 5, the meter bars also extend parallel to the row of fusible devices, and the latter alternate in presenting polarity terminals toward the meter bars, while these meter bars are of such a length that the same standard straps will serve for connecting polarity terminals with each other or with meter bars. However, a different length of connector would be required as a totalizer strap between the meter bars in the same row.

In Fig. 6, the meter terminals consist of simple posts each located equidistant from two polarity terminals, and two standard lengths of straps will suffice for connecting adjacent polarity terminals to each other and for connecting any polarity terminal to the nearest meter terminal.

In each of these embodiments it will be evident that the consumption circuit terminals are all conveniently close to the edges of the panel board; that the changeable connections all can readily be made upon the face of the board and with straps of standard lengths; that a glance at the board will show which consumption circuits are connected to any particular meter bar; and that the general arrangement requires only a comparatively small width of board.

I claim as my invention:

1. In a metering panel board, two rows of circuit-controlling devices each composed of consecutive groups of four, each group of four comprising two pairs of devices associated with two consumption circuits, all of the devices presenting their consumption-circuit terminals towards the outer sides of the rows, one device of each pair presenting

its other terminal as a polarity terminal at the inner sides of the rows, a supply-circuit conductor connected to the other or supply-circuit terminal of the other device of each pair, meter terminals at the inner side of the rows and each respectively opposite one group of the devices, and detachable straps for interchangeably connecting any meter terminal with either of the polarity terminals of the pairs of devices of the group opposite that terminal.

2. In a metering panel board, two rows of circuit-controlling devices composed of consecutive groups of four, each group of four comprising two pairs of devices associated with two consumption circuits, all of the devices presenting their consumption circuit terminals towards the outer side of the rows, one fusible device of each pair presenting its other terminal as a polarity terminal at the inner sides of the rows, a supply-circuit conductor connected to the other or supply-circuit terminal of the other device of each pair, meter terminals at the inner side of the rows and each respectively opposite one group of the devices, and detachable straps for interchangeably connecting any meter terminal with each of the polarity terminals of the devices of the group opposite that terminal and with one another, the meter terminals being in a row parallel to the aforesaid rows.

3. A metering panel as per claim 1, in combination with detachable straps for interchangeably connecting the last polarity terminal of the devices of any group with the first polarity terminals of the devices of the next group.

4. In a metering panel board, a row of circuit controlling devices composed of consecutive groups of four, each group of four comprising two pairs of devices associated with two consumption circuits, all of the devices presenting their consumption circuit terminals towards one side of the row, the first and fourth device of each group presenting their other terminals as polarity terminals at the other side of the row, a supply circuit conductor connected to the other or supply terminals of the second and third device of each group, meter terminals at the said other side of the row and each respectively opposite one group of the devices, and detachable straps for interchangeably connecting any meter terminal with the polarity terminal of either the first or the fourth device of the group opposite that terminal.

5. In a metering panel board, a row of circuit-controlling devices composed of consecutive groups of four, each group of four comprising two pairs of devices associated with two consumption circuits, all of the devices presenting their consumption-circuit terminals towards one side of the row, the first and fourth device of each group pre-

senting their other terminals as polarity terminals at the other side of the row, a supply-circuit conductor connected to the other or supply terminals of the second and third device of each group, meter terminals at the said other side of the row and each respectively opposite one group of the devices, and detachable straps for interchangeably connecting any meter terminal with the polarity terminal of either the first or the fourth device of the group opposite that terminal, the meter terminals being in a row parallel to the aforesaid row and spaced from the polarity terminals a distance equal to the distance between the meter terminals.

6. A metering panel as specified in claim 4, in combination with detachable straps for interchangeably connecting the polarity terminal of the fourth device of any group with the polarity terminal of the first device of the next group.

7. A metering panel as specified in claim 1, in combination with totalizer straps for interchangeably connecting consecutive meter terminals with one another.

8. A metering panel as specified in claim 1, in which the said members are all mounted on an insulating board with the circuit terminals of all of the devices adjacent to one edge of the board, and in which the said conductor is disposed behind the board.

9. A panel board comprising an insulating base, two parallel rows of consumption circuit controlling devices all having their consumption circuit terminals extending laterally outward of the said rows, the devices associated with each consumption circuit being consecutive, a neutral bus bar connected to the neutral terminal of one of each such pair of devices, the other device of each pair having its polarity terminal extending laterally inward of the said rows, meter terminals disposed between the aforesaid rows, and detachable connectors for connecting the meter terminals and the polarity terminals of the devices with one another.

10. A metering panel board as specified in claim 9, in which the meter terminals are disposed in two rows between and parallel to the aforesaid rows of devices, each meter terminal being effectively spaced by the same distance from the meter terminal parallel thereto and from the polarity terminals laterally opposite thereto.

11. A metering panel board as specified in claim 9, in which the meter terminal mem-

bers are disposed in two rows between and parallel to the aforesaid rows of devices and in which each terminal member has a pair of connecting portions laterally opposite respectively to the inwardly directed polarity terminals of two consecutive pairs of devices.

12. A metering panel board as specified in claim 9, in which the meter terminals are disposed in two rows between and parallel to the aforesaid rows of devices, each meter terminal comprising a bar corresponding substantially in length to the space occupied by two consecutive pairs of the devices, and having a pair of connecting portions respectively opposite the inwardly directed polarity terminals of the devices comprising the two pairs.

13. The combination with a distributing panel having two rows of circuit-controlling devices each divided in groups of four, the end devices of each group being provided with polarity terminals extending between the rows and spaced apart a distance equal to the center to center distance between the devices, of two rows of separate metering terminals between the rows of devices each having attaching means for connectors equidistantly spaced from similar means on adjacent meter terminals and from the said polarity terminals whereby the meter terminals may be connected to one another or to a polarity terminal by an interchangeable connector of predetermined length.

14. The combination with a distributing panel having two rows of circuit-controlling devices each divided in groups of four, the end devices of each group being provided with polarity terminals extending between the rows and spaced apart a distance equal to the center to center distance between the devices, of two rows of separate metering terminals between the rows of devices each having attaching means, the said means on each of four adjacent meter terminals being disposed in the corners of a square, having sides equal in length to the distance between the said means and an adjacent polarity terminal and between two adjacent polarity terminals, and interchangeable connectors for connecting the meter terminals, the polarity terminals or the former with the latter.

Signed at Chicago, Illinois, October 25, 1922.

ARTHUR C. McWILLIAMS.
